UNITED STATES PATENT OFFICE.

WILLIAM HATCHER BASKIN, OF MINEOLA, GEORGIA:

COTTON-GIN.

SPECIFICATION forming part of Letters Patent No. 741,443, dated October 13, 1903.

Application filed June 19, 1902. Serial No. 112,367. (No model.)

To all whom it may concern:

Be it known that I, WILLIAM HATCHER BASKIN, a citizen of the United States, residing at Mineola, in the county of Lowndes and 5 State of Georgia, have invented certain new and useful Improvements in Cotton-Gins; and I do hereby declare the following to be a full, clear, and exact description of the invention, such as will enable others skilled in the art to 10 to which it appertains to make and use the same.

My present invention relates to improvements in cotton-gins, and possesses among its novel features an improved driving mechanism for operating the various parts of the 15 gin from the main power-shaft and also an improved feeding mechanism designed to effectively regulate the amount of cotton fed to the rolls of the gin within narrow limits.

In order that my said invention may be 20 more readily understood, reference will be had to the accompanying drawings, wherein my said improvements are shown as embodied in a double-roller cotton-gin constructed in accordance with the improvements 25 covered by Letters Patent of the United States, No. 616,761, granted to me on December 27, 1898.

In the drawings, Figure 1 is a side elevation of the gin. Fig. 2 is an end elevation of the 30 same looking from one end of the machine, the end boards 69, carrying the feed-rolls and their driving-chains, being removed. Fig. 3 is a similar view looking at the same end of the machine, parts of the driving mechanism 35 removed; and Fig. 4 represents a section taken transversely through the gin, showing the roller-feed mechanism in detail.

In the views, 1 2 are the two end frames of the machine connected together by the upper 40 and lower tie-bars 3 4, respectively, bolted or otherwise secured to the end frames. Immediately within the end frame 1 is located an A-frame 5, carrying bolts 6, resting in slots 7 in the end frame 1, by means of which a horizontal adjustment is provided between said 45 end frame 1 and the A-frame 5. This frame 5 carries at its upper end a bearing 8, providing a suitable journal for the shaft 9. Mounted preferably immediately outside the end 50 frame 1 upon the same end of the machine is a second A-frame, 10. This frame 10 preferably rests upon the floor or other suitable

support or foundation and may be held firmly in place in any desired manner, such as bolting to the end frame 2, relative movement between these frames being necessarily prevented. This frame 10 is provided about midway of its height with a recess 11, in which rests the journal 12, forming a bearing for the shaft 9. This journal 12 is movable vertically in this recess and is acted upon by the coiled spring 13, the compression of which is adjusted through the set-screw 14.

The power-shaft 19 is provided near its outer end with the belt-pulleys 15 16, through 65 which power is supplied to the gin. Inside between the end frames 1 10 of the machine is mounted a friction-wheel 17, preferably immediately adjacent the frame 10, which wheel bears resiliently against the friction-wheel 18 upon the shaft 19. These wheels or pulleys are composed of some suitable material, paper being found suitable for the purpose. The end of the shaft 19, carrying the friction-wheel 18, is journaled in the bearing 70 20 in the upper end of the frame 10, the opposite end of the shaft being mounted in the pillow-block 21, carried by the end frame 2.

22 is a pinion securely mounted upon one end of the shaft 9 immediately adjacent the 80 bearing 8 upon the frame 5. Meshing with this pinion 22 is a gear-wheel 23, which in turn meshes with the gear-wheel 24. These gear-wheels are preferably of the same size and are mounted upon the inner ends of the 85 stud-shafts 25 26, respectively, each of said shafts being mounted in a bearing 27 28, respectively, hung from the end frame 1. Upon the outer ends of these stud-shafts 25 26, respectively, are mounted sprocket-wheels 90 29 30, respectively.

Mounted upon each end of the shaft 19 is an eccentric 31 at the same angle upon said shaft. Mounted directly above this shaft 19 is a rock-shaft 32, mounted in the bearings 95 33 in the upper portion of the machine. This shaft 32 carries upon each end a yoke 34, in the lower ends of which ride eccentrics 31 upon the shaft 19. Double oppositely-disposed arms 35 are carried upon the shaft 32 100 at spaced intervals, upon the ends of which are carried curved arms 36, the curvature of said blades forming an arc of a circle struck from the shaft 32 as a center. Immediately

outside the arms 35 are the rollers 37 38, mounted upon the shafts 39 40, respectively, mounted upon the swinging arms 41 42, respectively. These swinging arms 41 42, respectively, are pivotally mounted upon the studs 43 44, respectively, secured to the end frames 1 and 2.

45 46, respectively, are springs acting upon the shafts 39 40, respectively, carrying said rollers 37 38, the tension of said springs being increased or decreased by means of the set-screws 47 48, respectively. These rollers 37 38 each carry upon one end of the shaft a sprocket-wheel 49 50, respectively, over which 15 pass chains 51 52, passing over the gear-wheels 29 30, respectively. These rollers 37 38 carry upon their peripheries an elastic covering 53 54, respectively, such as very thick leather or other suitable material, either grooved or 20 otherwise, as may be desired.

Journaled in the end frame 1 2, directly over the rock-shaft 32, is a rotating shaft 55, carrying near each end thereof an eccentric 56. Upon this eccentric 56 are mounted double arms 57, preferably diverging downwardly. Upon each end of these diverging arms are pivoted brackets 58, each secured to the longitudinally-disposed feeding-boards 59, each resting upon the inclined slotted 30 plates 60, constituting seed-grates. These seed-grates 60 extend from one end of the machine to the other in front of the rollers 37 38 and have their outer ends in close proximity thereto. These feeding-boards 59 slide back and forth upon the upper side of these seed-grates 60 through the action of the eccentric 35 56 upon the shaft 55.

Upon the upper extension 61 of the end frames of the gin are recesses 62, within 40 which are located the bars 63, carrying upon their lower ends the knife-blades 64, bearing upon the elastic covering of the rollers 37 38, respectively. These blades are so shaped and disposed as to be clear of the path of the 45 curved oscillating blades 36 upon the rocker-arms 35, and said blades may be adjusted as desired by means of the bolts 65 66', acting upon the bars 63, carrying said blades.

Mounted directly above the feeding-boards 50 59 are the feeding-rollers 66 67, respectively, each provided upon its periphery with spirally-arranged teeth or spikes 68. These rollers 66 67 are preferably mounted at each end in the end pieces 69, closely fitting upon 55 the top of the machine between the extensions 61 61, the same being so secured as to allow the parts to be readily lifted out, together with the feeder-rollers 66 67. The feed-rollers 66 67 revolve in the same direction as the 60 rollers 37 and 38 and in close proximity to the periphery of the rollers 37 38 and co-operate with the feeder-boards 59, working back and forth upon the seed-grates 60. These feed-rollers may be driven through 65 sprockets 70 71, respectively, connected to the sprocket-wheels 72 73, respectively, upon the shafts 39 40, respectively, through the

chains 74 75. The shaft 55 may be similarly driven through the sprocket-wheel 76, connected to a sprocket-wheel upon one of the 70 shafts of the feed-rollers through the chain 77.

The operation of the gin is as follows: Power is applied to the power-shaft 19 from any suitable source. The friction-wheel 18, carried by the shaft 19, will impart motion to 75 the friction-wheel 17 upon the shaft 9, causing the same to rotate. This will cause the eccentric 31, carried upon each end of said shaft 19, to rock or oscillate the rock-shaft 32 through the yokes 34. On the other end 80 of the shaft 9 the pinion 22 will impart its motion to the gear-wheel 23, which in turn imparts its motion to the gear-wheel 24, these gears 23 24 revolving in opposite directions. These gears through their respective shafts 85 impart motion to the sprockets 29 30, respectively, which in turn transmit power to the rollers 37 38 through the chains 51 52, respectively, said rollers revolving in the direction indicated by the arrows, Fig. 4. Connected to sprocket-wheels 72 73, respectively, upon the shafts 39 40 of the rollers 37 38, respectively, through the chains 74 75, respectively, are sprockets 70 71, connected to the feed-rollers 66 67, respectively, said feed-rollers being thereby caused to revolve in the same direction with the rollers 37 38, respectively, as indicated by the arrows in Fig. 4. The sprocket-wheel 76 upon the eccentric-shaft 55 is preferably connected to a sprocket upon 90 one of the roller-shafts, such as by a sprocket-chain 77. This motion thus imparted will cause the double arms 58, riding upon the eccentricities 56, to reciprocate the feeding-boards 59 back and forth over the slotted seed-grates 105 60, while the rocking motion imparted to the rock-shaft 32 will cause the double arms 35, carrying the curved blades, to oscillate between said feed-boards 59 and the rollers 37 38, said blades working in close proximity to 110 the elastic covering upon said rollers and said blades 64. Cotton may now be fed into the gin between the end pieces 69 and over the feeding-rollers 66 67. These rollers 66 67, carrying spikes 68, will feed the cotton between 115 the rollers 37 38 and the reciprocating boards 59. These boards 59 move the cotton, ordinarily containing much seed, back and forth over the slotted seed-grates 60 60, also pressing the cotton against the rollers, causing the seed 120 to become separated from the cotton and to disappear through said grate, where they may be collected in any desired manner. In the meantime the curved blades 36, acting in close proximity to the periphery of the 125 rollers 37 38, will feed the cotton thus freed from seed up beneath the knife-blades 64 64 and assisted by the rotation of the rollers 37 38 will be carried over the same, the cotton being stripped therefrom in any suitable 130 well-known manner. These knife-blades are adjusted through the set-screws 65 and 66 to be in such proximity to the surface of the rollers 37 38 that the cotton will be drawn

- therebetween in very small quantities, seeds and other enlargements or obstructions being excluded. However, should an uneven quantity of cotton pass between the knife-blades 64 and the rollers 37 38 said rollers will yield through the resilient pressure of the springs 45 46, allowing the same to pass said knives. The fact that the feed-rollers 66 67 are located in the position shown in 5 Fig. 4 allows the amount of cotton fed to the rollers 37 38 to be regulated within very narrow limits, as the excess of cotton is automatically returned to the bin formed upon the top of the gin by these feed-rollers 66 67. 10 Thus it will be seen that a feeding device is provided whereby cotton is brought forward to the working point before the rollers when needed and the surplus is automatically returned, an excess of cotton at the working 15 point retarding the operation of the machine.

I have shown my invention as embodied in but one form of machine; but it will be understood that I do not so limit myself, and while my invention is especially designed as 20 an improvement upon my former Letters Patent aforesaid it will be understood my improvements are applicable to the various forms of gins now in common use, and while I have employed certain details of construction 25 in the embodiment of my invention herein shown and described it is obvious that many changes and modifications may be made therein, which changes and modifications could be made without departing from the 30 spirit of my said invention.

Having thus described my invention, what I claim, and desire to secure by Letters Patent of the United States, is—

1. In a cotton-gin, the combination with a 40 pair of main rollers, knives coöperating therewith, and a curved oscillating blade coöperating with said rollers and knives, of feed-rolls mounted in proximity to said blades and said rollers and knives, and spirally-arranged 45 spikes carried by said rolls for feeding cotton to said rollers and knives.

2. In a cotton-gin, the combination with the main rollers, knives coöperating therewith, curved oscillating blades, and reciprocating 50 feed-boards, working to and fro before said rollers, of feed-rolls mounted above said reciprocating boards, and spirally-arranged spikes carried by said rolls for feeding cotton to said rollers.

55 3. In a cotton-gin, the combination with the main rollers, knives coöperating with said rollers, curved oscillating blades coöperating with said rollers and knives, seed-grates, and feed-boards reciprocating upon said seed- 60 grates, of feed-rolls mounted above said seed-grates, and spirally-arranged spikes carried by said rolls for feeding cotton to said parts.

4. In a cotton-gin, the combination with a 65 pair of main rollers mounted at spaced distances upon the machine, of a pair of feeding-rolls mounted between said main rollers,

and removable end pieces supporting said feeding-rolls.

5. In a cotton-gin, the combination with a pair of main rollers mounted at spaced distances upon the machine, of a pair of feeding-rolls mounted between said main rollers, removable end pieces supporting said feeding-rolls, and means carried by said feeding-rolls for feeding the cotton to said main rollers. 70 75

6. In a cotton-gin, the combination with a pair of main rollers mounted at spaced distances upon the machine, of a pair of feeding-rolls mounted between said main rollers, removable end pieces supporting said feeding-rolls, and a spiral row of spikes carried by said feeding-rolls for feeding the cotton to said main rollers. 80

7. In a cotton-gin, the combination with a pair of spaced elastic rollers, adjustable knife-blades coöperating therewith, seed-grates, reciprocating feeder-boards mounted thereon and curved blades coöperating with said rollers, knives and feed-boards, of a pair of feed-rolls mounted above said seed-grates between 90 and in close proximity to said rollers, and spirally-arranged spikes carried by said feed-rolls for maintaining a uniform supply of cotton before said rolls. 85

8. In a cotton-gin, the combination with a pair of spaced elastic rollers, adjustable knife-blades coöperating therewith, seed-grates, reciprocating feeder-boards mounted thereon and curved blades coöperating with said rollers, knives and feed-boards, of a pair of feed-rolls mounted above said seed-grates between 95 and in close proximity to said rollers, and spirally-arranged spikes carried by said feed-rolls and coöperating with said reciprocating boards for maintaining a uniform supply of cotton before said rolls. 100 105

9. In a cotton-gin, the combination with the main rollers, and a rock-shaft carrying curved blades coöperating with said rollers, of a yoke upon each end of said rock-shaft, a rotating 110 shaft immediately beneath said rock-shaft and eccentrics carried by said rotating shaft and coöperating with said yokes to rock said rock-shaft.

10. In a cotton-gin, the combination with 115 the end frames of the machine and the main rollers mounted therein, of a rock-shaft carrying curved blades also mounted in said frames between said rollers, yokes carried by said rock-shaft, a rotating shaft mounted in 120 said frames beneath said rock-shaft, eccentrics carried by said rotating shaft and embraced by said yokes, a main power-shaft, and a pair of friction-wheels carried by said rotating and power shafts. 125

11. In a cotton-gin, the combination with the end frames of the machine and the main rollers mounted therein, of a rock-shaft carrying curved blades also mounted in said frames between said rollers, yokes carried by 130 said rock-shaft, a rotating shaft mounted in said frames beneath said rock-shaft, eccen-

trics carried by said rotating shaft and embraced by said yokes, a main power-shaft, a pair of friction-wheels carried by said rotating and power shafts, and means for exerting a yielding pressure upon said friction-wheels.

12. In a cotton-gin, the combination with the end frames of the machine and the main rollers mounted therein, of a rock-shaft carrying curved blades also mounted in said frames between said rollers, yokes carried by said rock-shaft, a rotating shaft mounted in said frames beneath said rock-shaft, eccentrics carried by said rotating shaft and embraced by said yokes, a main power-shaft, a pair of friction-wheels carried by said rotating and power shafts, and an adjustable bearing adjacent said friction-wheels through which said power-shaft passes for exerting a yielding pressure upon said friction-wheels.

13. In a cotton-gin, the combination with the end frames of the machine and the main

rollers mounted therein, of a rock-shaft carrying curved blades mounted in said end frames between said rollers, yokes carried by 25 said rock-shaft, a rotating shaft mounted in said end frames beneath said rock-shaft, eccentrics mounted on said rotating shaft and embraced by said yokes, sprocket-wheels carried by said rollers, a pair of meshing gears 30 mounted in said end frames, sprocket-wheels connected to said gears, connected to the sprockets upon said rollers by sprocket-chains, a power-shaft, a pinion carried by said power-shaft meshing with one of said 35 gears, and a friction-wheel upon said rotating shaft engaging a friction-wheel upon said power-shaft.

In testimony whereof I affix my signature in presence of two witnesses.
